UNITED STATES PATENT OFFICE.

WALTER H. WHITE, OF KENOSHA, WISCONSIN.

LAMP.

1,177,076.

Specification of Letters Patent. Patented Mar. 28, 1916.

Application filed April 29, 1914. Serial No. 835,084.

To all whom it may concern:

Be it known that I, WALTER H. WHITE, a citizen of the United States, and resident of Kenosha, in the county of Kenosha and State of Wisconsin, have invented new and useful Improvements in Lamps, of which the following is a description, reference being had to the accompanying drawings, which are a part of this specification.

This invention relates to improvements in lamps, and while more particularly adapted for limousine use may be used for other illuminating purposes.

Limousine lamps as now ordinarily constructed are formed of stamped, spun or cast metal parts which are soldered together to form the frame of the lamp and into portions of said frame the strips of glass forming the shell are mounted. Lamps of this type are comparatively expensive to manufacture and are otherwise unsatisfactory.

It is one of the objects of the present invention to overcome the before mentioned objectionable features and provide a lamp for limousine and other uses in which the use of solder is almost entirely eliminated and the inclosing glass shell is formed of one piece and one portion of the shell is silvered to form a reflecting surface adapted to direct the rays of light from one side of the lamp.

A further object of the invention is to provide a lamp in which most of the parts are formed of sheet metal and are removably connected together in a simple manner which will easily permit parts being separated for repairs or for cleaning purposes.

A further object of the invention is to provide a lamp of the type mentioned which is of simple and durable construction, is inexpensive to manufacture and is well adapted for the purpose described.

With the above and other objects in view the invention consists of the improved lamp and its parts and combinations as set forth in the claims, and all equivalents thereof.

In the accompanying drawing in which the same reference characters indicate the same parts in all of the views: Figure 1 is a central vertical sectional view of the improved lamp in limousine form, parts broken away to show interior construction; Fig. 2 is a transverse sectional view thereof taken on line 2-2 of Fig. 1; and Fig. 3 is a top fragmentary detail view of the lamp.

Referring to the drawing the numeral 5

indicates a supporting or connector tube to which the improved lamp 6 is removably connected.

The tube is provided with an annular flange 7 on its lower end and a coupling nut 8 surrounding said flange is adapted to engage the threaded upper end plug 9 of the lamp and clamp the lamp to the supporting tube. The tube incloses terminal wires 10 which connect to a source of electrical supply and which are adapted to be engaged by the socket terminals 11 of the incandescent bulb tube 12. The terminals 11 are insulated from each other and the tube and at their lower ends are provided with yielding contacts 13 which are engaged by the terminals 14 of the incandescent bulb 15. The bulb is of the ordinary construction and is locked to the tube by the ordinary bayonet joint 16 common to this type of lamp to provide for easily replacing the electric lamps.

The upper end of the lamp tube is threaded into the upper end plug 9 and the lower end of the tube is provided with an annular upturned curved flange 17 which has a threaded engagement 18 with a curved annular reflector plate 19. A similar plate 20 having its outer peripheral edge portion 21 resting upon the outer peripheral edge portion 22 of the lower plate extends upwardly therefrom and the upper inner edge portion 23 of said upper plate is supported on the annular shoulder 24 of the plug 9. These two plates in connection with the lamp tube and the plug form the upper portion of the lamp and to which the depending shell or globe 25 is connected. This shell is formed of one piece of glass of any desirable shape and its upper peripheral edge 26 is flanged outwardly and is provided with an annular groove 27 to receive the lower inner annular edge 28 of the annular clamping member 29.

The clamping member is in the form of a grooved split ring having radial projecting apertured ends 30 through which a clamping bolt 31 extends. A nut 32 on the end of the bolt co-acts with the bolt to clampingly draw the ring ends together.

The ring is placed around the peripheral edge portions of the plates with the edge portions extending into the groove 27 of the ring and the lower edge 28 of the ring extending into the groove of the shell and the ring ends are then drawn together by means

of the clamping screw and nut. A gasket 34 of yielding material is interposed between the flange of the shell and the peripheral edge portion of the lower plate to 5 cushion the said shell.

In limousine lamps it is desirable to have the light reflected only from one side of the lamp and in order to accomplish this result the inner half of the glass of the shell is 10 silvered as indicated by the numeral 35 to provide a reflecting surface.

From the foregoing description it will be seen that the lamp is of very simple construction and is well adapted for the purpose described.

What I claim as my invention is:

1. A lamp, comprising a tubular member containing circuit wires and having an incandescent electric bulb mounted on one end, 20 an annular plate mounted on the tube, an annular reflector plate mounted on the tube adjacent the electric bulb, a shell inclosing the reflector plate and the bulb and having one end portion positioned adjacent the edge portion of one of the plates, a member 25 removably locking the shell end to one of the plates, and means for connecting the tubular member to a support, said support having circuit wires which are constructed 30 to be connected to the circuit wires of the tubular member.

2. A lamp, comprising a tubular member constructed to carry an incandescent bulb, curved annular plates mounted on the tube, 35 a shell having its open end portion bearing against one of the plates, an annular grooved member extending over the peripheral edges of the plates and engaging and locking the shell to the plates, and means 40 for removably connecting the tube to a support provided with electrical terminals.

3. A lamp, comprising a tubular member constructed to carry an incandescent bulb, an upturned curved annular deflector plate 45 connected to the lower end of the tube, a downwardly curved annular plate connected to the upper end portion of the tube and having its outer peripheral edge engaging the similar edge of the lower plate, a shell 50 having an upper peripheral edge which

bears against the peripheral edge of one of the plates, a grooved clamping ring extending around the peripheral edge portions of the plates and the shell to removably lock the parts together, and means for removably connecting the tube to a support provided with electrical terminals. 55

4. A lamp, comprising a tubular member constructed to carry an incandescent bulb, an upturned curved annular deflector plate 60 connected to the lower end of the tube, a downwardly curved annular plate connected to the upper end portion of the tube and having its outer peripheral edge engaging the similar edge of the lower plate, a shell 65 having an upper peripheral edge which bears against the peripheral edge of one of the plates, a grooved and split clamping ring extending around the peripheral edge portions of the plates and the shell to removably lock the parts together, and means for removably connecting the upper end of the tube to a support provided with electrical terminals.

5. A lamp, comprising a tubular member 70 constructed to carry an incandescent bulb, the lower end of the tube having a threaded flange formed thereon, an upturned curved annular plate threaded on the flange, a plug 75 threaded on the upper end of the tube, a downwardly curved annular plate connected to the plug and having its outer peripheral edge portion resting on the similar portion of the other plate, a shell having an upper open flanged end which engages one 80 of the peripheral edges of one of the plates, said shell flange having an annular groove, a split and grooved clamping ring extending around the peripheral edges of the plates and into the groove of the shell, a 85 threaded means for drawing the split ends of the ring together, and means for removably connecting the plug to a support provided with electrical terminals.

In testimony whereof, I affix my signature, in presence of two witnesses.

WALTER H. WHITE.
